G. A. ANDERSON

TRUCK SIDE FRAME

Filed Oct. 17, 1922

Inventor

Gustaf A. Anderson

By Ernest J. Melvin
his Attorney

UNITED STATES PATENT OFFICE.

GUSTAF A. ANDERSON, OF BALTIMORE, MARYLAND, ASSIGNOR, BY MESNE ASSIGNMENTS, TO THE SYMINGTON COMPANY, A CORPORATION OF MARYLAND.

TRUCK SIDE FRAME.

Application filed October 17, 1922. Serial No. 595,097.

To all whom it may concern:

Be it known that I, GUSTAF A. ANDERSON, a citizen of the United States, residing at Baltimore, in the State of Maryland, have invented certain new and useful Improvements in Truck Side Frames; and I do hereby declare the following to be a full, clear, and exact description of the invention, such as will enable others skilled in the art to which it appertains to make and use the same.

My invention relates to side frames for car trucks and has been primarily designed to provide a construction which is very strong and stiff but comparatively light in weight and in which costs incident to maintenance are reduced to a minimum.

The invention, generally stated, resides in forming a car truck side frame from a sheet or blank of metal folded to provide an inner wall and an outer wall arranged in spaced relation, each of said walls having a plurality of truck column portions, a plurality of top arch bar portions, a plurality of bottom arch bar portions, and a plurality of pedestal tie bar portions.

One of the principal features of the invention, particularly stated, involves the production of a car truck side frame from a continuous blank or sheet of wrought metal shaped to form inner and outer spaced side walls, said blank being folded at the top and having its edges joined by integral tie means at points outside of a vertical plane passing through the side frame, thereby facilitating the uniting of the walls in a firm and rapid manner.

Another object of the invention is to provide a pressed metal car truck side frame in which the side wall portions are provided with conveniently disposed flanges adapted to be easily united by rivets or similar means, some of said flanges projecting horizontally beyond the outer side wall of the side frame and other of said flanges being disposed centrally and vertically of said side frame.

A further feature of the invention resides in the production of a car truck side frame including inner and outer spaced metallic side walls, each of said walls being formed with window openings having bordering stiffening flanges extending inwardly of the side walls, and means involving an ex-

panded tubular member adapted to firmly 55 tie said side walls together, said tubular member being preferably inserted so as to maintain the inwardly extending stiffening flanges in abutted relation.

A still further object of the invention is to 60 provide a car truck side frame of pressed metal involving spaced inner and outer side walls, each of said walls having corresponding side frame sections including bottom arch bar portions, said bottom arch bar por- 65 tions being arranged to overlie each other above the journal boxes and having adjacent portions bendable about the heads of the journal box bolts for locking the same in position.

The invention further consists in the method of manufacturing a car truck side frame by forming the same from a continuous sheet metal blank having corresponding side frame portions which are symmetrically disposed with respect to an axis of symmetry passing between them, bending portions of said blank to form flanges, uniting said flanges, slitting opposite end portions of the blank, folding the blank along a line at the 80 top of the side frame and intermediate the ends thereof, said line being parallel to the said axis of symmetry and disposed between the slitted end portions, bending portions of the blank inwardly adjacent the slitted ends 85 to form cambered top arch bar portions, and finally welding said last named bent portions.

There are other features of the invention pertaining to particular arrangement of 90 parts and details of construction, all as will hereinafter appear.

In the drawings illustrating the invention, the scope whereof is pointed out in the claims:

Figure 1 is a view in side elevation of a car truck side frame embodying the invention, the wheels of the car truck being shown diagrammatically in dotted lines.

Figure 2 is a vertical transverse sectional view on the line 2-2 of Figure 1.

Figure 3 is a top plan view of a one-half portion of the side frame.

Figure 4 is a horizontal sectional view of a one half portion of the side frame on the line 4-4 of Figure 1.

Figure 5 is an enlarged detail cross sectional view on the line 5-5 of Figure 1.

Figure 6 is an enlarged detail vertical cross sectional view on the line 6-6 of Figure 1.

Referring to the drawings in which similar reference characters designate corresponding parts in the several views, my improved side frame includes an outer wall 1 and an inner wall 2 formed from a continuous sheet or blank of metal, the top intermediate portion of said blank being folded along a straight line parallel to the axis of symmetry of said blank. The walls are arranged in spaced relation, and each comprises truck column portions 3, top arch bar portions 4, bottom arch bar portions 5 and pedestal tie bar portions 6.

The bolster opening is indicated by the numeral 7, said opening being formed between the truck column portions of the side frame, as will be understood. Inwardly extending flanges 8 are provided on the truck column portions, the adjacent edges of said flanges being welded at a plurality of spaced intervals, as indicated by the numeral 9 in Figure 2. Spaces 10 are preferably provided between the welded portions of the flanges provided on the truck column portions. The inwardly extending flanges 8 are preferably continued around the corner bends uniting the truck column portions with the bottom arch bar portions, said flanges extending across and bordering the lower edge of the bolster opening. The weld at the corner bend is also preferably continued around said bend and serves to unite the continued flanges at the bottom of the bolster opening, as shown in Figure 4. The inwardly extending flanges bordering the bottom of the bolster opening are preferably spaced apart intermediate the truck columns to provide an opening 11. The upper ends of the flanges 8 provided on the truck column portions are preferably continued so as to provide inwardly extending flanges 12 on the lower edges of the top arch bar portions of the truck.

Each side wall of the side frame is provided with a window, said window being surrounded by an inwardly extending flange 13. Oppositely inwardly extending flanges 13 of the side walls are preferably abutted centrally of the side frame, as shown in Figure 5. The side walls are adapted to be united by means of expanded tubular members 14, said tubular members being inserted within the window openings and having their opposite ends expanded to firmly engage the annular faces formed at the junctions of the respective side walls with their inwardly extending flanges 13. This type of tie means serves to firmly unite the side walls without materially increasing the weight of the side frame. It will also be obvious that the annular flanges 13 and the inserted tubular members 14 provide con-

tinuous stiffening means at the respective edges of the bolster column portions, the top arch bar portions and the bottom arch bar portions.

The edges of the folded sheet metal blank are designed to be united intermediate the ends of the side frame and at points outside of a vertical plane passing through said side frame. The means uniting the side walls at the bottom of the side frame includes a bottom flange 15 formed integral with the inner wall 2 and an adjacent flange 16 formed integral with the outer wall 1 of the side frame, the outer edges of said adjacent flanges 15 and 16 being firmly united by a plurality of rivets 17 beyond the face of the outer side wall 1. The flanges 15 and 16 are formed integral with the continuous sheet metal blank and the joint uniting the same is preferably at a point outside of the side frame, thereby permitting the rapid and comparatively easy insertion of the connecting rivets.

The flange 15 is upwardly inclined at each end of the side frame and merges into the pedestal tie bar portions 6, which latter portions project beneath the journal boxes. The flange 16 terminates short of the journal boxes and at its outer end is provided with an inwardly tapering flange 18 adapted to extend around the corner bends at the junctions of the pedestal tie bar portions and bottom arch bar portions. A similarly tapered inwardly extending flange 19 projects from the inner side wall 2 and around the adjacent portion of said corner bend. These flanged portions of the pedestal tie bar members which are located between the truck columns and the adjacent journal boxes are preferably of tapering form, their greatest cross sectional area being at the junctions of the pedestal tie bar portions with the respective truck columns. Journal box bolt openings 19 are provided in the pedestal tie bar portions 6.

The bottom arch bar portions 5 which extend at an angle to the top arch bar portions and to the pedestal tie bar portions, merge with and are integrally united to said top arch bar portions of the respective inner and outer walls above the journal boxes at the ends of the truck. Each bottom arch bar portion includes an angular flange, the horizontal web of which is indicated by the numeral 20 and the vertical web of which is indicated by the numeral 21. The angular flanges provide a strong and durable construction, the inwardly extending portions 20 being prolonged to extend over the journal boxes at each end of the side frame, and the vertically disposed portions 21 being abutted centrally and longitudinally of the truck and united by a plurality of rivets 22. The respective portions 20 and 21 of the angular flanges forming the bottom arch

bars are designed to extend around the corner bend at the junctions of said bottom arch bars with the pedestal tie bar portions, thereby greatly increasing the strength of 5 the truck so that failure of the side frame at these points is reduced to a minimum. The vertical disposition of the portions 21 of the angular flanges permits of the ready insertion of the connecting rivets.

10 The prolonged extensions of the bottom arch bars which project over the journal boxes are indicated by the numeral 23, said extensions being preferably overlapped, as best shown in Figure 6. The edge of one of 15 said extensions is adapted to be bent upwardly, as indicated at 24, adjacent the head of one of the journal box bolts indicated in dot and dash lines in Figure 6. This construction of bendable extension provides a 20 means which prevents the turning of the journal box bolts, as will be understood.

The top portion of the side frame is preferably arranged in the form of a cambered compression member, each end portion of the 25 sheet metal blank being slit, as indicated at 25, to provide inwardly extending flanges 26 arranged to meet adjacent a line passing through the center of the side frame. The blank is also transversely slitted, as indicated at 27, to permit the top portion of the 30 side frame at its ends to be properly bent to produce the cambered effect. The inwardly extending flanges 26 are adapted to be welded along their inner opposed edges, 35 said weld extending around the ends of said flanges adjacent the transverse slit 27. The longitudinal and transverse welding of the slitted ends of the top portion of the side frame is indicated by the numeral 28.

40 Journal box bolt openings 29 may be provided in the inwardly extending flanges 26 at each end of the side frame, the extreme outer ends of the top portion of the side frame being angled off, as shown, to permit 45 the ready insertion of the adjacent journal box bolts.

The method of manufacturing my improved car truck side frame consists in shaping a continuous sheet metal blank having 50 corresponding side frame portions which are symmetrically disposed with respect to an axis of symmetry of the blank passing between them, slitting opposite end portions of the blank longitudinally and transversely 55 to provide a cambered top arch bar, bending portions of said blank to form flanges, which flanges provide the integral tie means for the side walls of the side frame, folding the blank along a line at the top of the side frame and intermediate the ends thereof, said line being parallel to the said axis of symmetry and arranged between the slitted end portions of the blank, and finally uniting said slitted portions and said flanges. 60 It will also be perceived that my method of

manufacturing car truck side frames involves the overlapping of the prolonged extensions of the bottom arch bar portions to provide a simple and effective locking means for the journal box bolts. 70

A car truck side frame constructed in accordance with my present invention is light in weight, strong and durable, the joining of the side frame portions by integral flanges forming the tie means thereof providing a 75 greatly reinforced and reliable structure in which simplicity of manufacture and rapidity of assembly are achieved.

I claim:

1. A car truck side frame involving a continuous metal sheet shaped to form an outer wall and an inner wall arranged in spaced relation, each of said walls having a plurality of truck column portions, a plurality of top arch bar portions, a plurality of bottom arch bar portions, and a plurality of pedestal tie bar portions; flanges formed integral with and projecting beyond said side walls at one side of the side frame, and means uniting said flanges. 80

2. A car truck side frame involving a continuous metal sheet shaped to form an outer wall and an inner wall arranged in spaced relation, each of said walls having a plurality of truck column portions, a plurality of top arch bar portions, a plurality of bottom arch bar portions, and a plurality of pedestal tie bar portions; flanges carried by the inner and outer walls, said flanges being adapted to project beyond said outer wall 85 only, and means uniting said flanges. 90

3. A pressed metal car truck side frame including outer and inner walls arranged in spaced relation, each of said walls having a plurality of truck column portions, a plurality of top arch bar portions, a plurality of bottom arch bar portions, and a plurality of pedestal tie bar portions; and means uniting said side walls, said means being located 95 at a point outside of a vertical plane passing between said walls. 100

4. A pressed metal car truck side frame including outer and inner walls arranged in spaced relation, each of said walls having a plurality of truck column portions, a plurality of top arch bar portions, a plurality of bottom arch bar portions, and a plurality of pedestal tie bar portions; flanges projecting from one side of the side frame, and means uniting said flanges at 110 points outside of one of said walls. 115

5. A pressed metal car truck side frame including outer and inner walls arranged in spaced relation, each of said walls having a plurality of truck column portions, a plurality of top arch bar portions, a plurality of bottom arch bar portions, and a plurality of pedestal tie bar portions; and means uniting said side walls at points outside of at least one of said walls, said means 125 130

4

terminating short of the ends of the side frame and arranged to extend beneath said truck column portions.

6. A pressed metal car truck side frame including outer and inner walls arranged in spaced relation, each of said walls having a plurality of truck column portions, a plurality of top arch bar portions, a plurality of bottom arch bar portions, and a plurality of pedestal tie bar portions; and rivet means uniting said side walls, said rivet means being longitudinally of the truck and in a plane beyond the outer face of one of said side walls.

7. A pressed metal car truck side frame including outer and inner walls arranged in spaced relation, each of said walls having a plurality of truck column portions, a plurality of top arch bar portions, a plurality of bottom arch bar portions, and a plurality of pedestal tie bar portions; integral tie means including flanges provided on said walls, said flanges being adapted to merge into the pedestal tie bar portions beyond the truck column portions, and means uniting said flanges throughout their length at the bottom of the side frame.

8. A pressed metal car truck side frame including outer and inner walls arranged in spaced relation, each of said walls having a plurality of truck column portions, a plurality of top arch bar portions, a plurality of bottom arch bar portions, and a plurality of pedestal tie bar portions; integral tie means including horizontally projecting abutted flanges provided on said walls at the bottom of the truck and vertically disposed abutted flanges provided on said bottom arch bar portions, and means uniting each series of said abutted flanges.

9. A pressed metal car truck side frame including outer and inner walls arranged in spaced relation, each of said walls having a plurality of truck column portions, a plurality of top arch bar portions, a plurality of bottom arch bar portions, and a plurality of pedestal tie bar portions; and integral means including flanges projecting from the side frame walls, some of said flanges being united at points outside of a vertical plane passing between the side walls, and other of said flanges being united at points within said vertical plane.

10. A pressed metal car truck side frame including outer and inner walls arranged in spaced relation, each of said walls having a plurality of truck column portions, a plurality of top arch bar portions, a plurality of bottom arch bar portions, and a plurality of pedestal tie bar portions; and integral tie means including flanges projecting from the side frame members, certain of said flanges being abutted and united adjacent the lower ends of the truck column portions and pedestal tie bar portions, and other of said

flanges being abutted and united adjacent said bottom arch bar portions.

11. A car truck side frame involving a continuous metal blank folded at its top to form spaced inner and outer side walls, each of said walls having a plurality of truck column portions, a plurality of top arch bar portions, a plurality of bottom arch bar portions, and a plurality of pedestal tie bar portions; and means including outwardly projecting flanges carried by said pedestal tie bar portions adjacent the outer side wall of the side frame, said flanges being adapted to extend beneath the truck column portions for uniting said side walls.

12. A car truck side frame involving a continuous metal blank folded at its top to form spaced inner and outer side walls, each of said side walls having a plurality of truck column portions, a plurality of top arch bar portions, a plurality of bottom arch bar portions, and a plurality of pedestal tie bar portions; and means uniting said side walls, said means including outwardly and inwardly projecting flanges provided on said pedestal tie bar portions, said flanges being adapted to extend around the corner bends at the junctions of said bottom arch bar portions with said pedestal tie bar portions, said outwardly projecting flanges being arranged to extend beyond the outer face of one of said side walls.

13. A pressed metal car truck side frame including inner and outer walls arranged in spaced relation, each of said walls having a plurality of truck column portions, a plurality of top arch bar portions, a plurality of bottom arch bar portions, and a plurality of pedestal tie bar portions; said bottom arch bar portions being provided with angularly disposed flanges having portions projecting inwardly and downwardly of the side walls, and means uniting said downwardly extending portions of said flanges.

14. A pressed metal car truck side frame including inner and outer walls arranged in spaced relation, each of said walls having a plurality of truck column portions, a plurality of top arch bar portions, a plurality of bottom arch bar portions, and a plurality of pedestal tie bar portions; said bottom arch bar portions being provided with vertically disposed flanges adapted to be united in a central and vertical plane passing through the side frame.

15. A pressed metal car truck side frame including inner and outer walls arranged in spaced relation, each of said walls having a plurality of truck column portions, a plurality of top arch bar portions, a plurality of bottom arch bar portions, and a plurality of pedestal tie bar portions; said bottom arch bar portions having inwardly extending flanges provided with prolonged exten-

sions, said extensions being overlapped above the journal boxes and at least one of said extensions having a portion adapted to be bent adjacent the head of a journal box 5 bolt.

16. A pressed metal car truck side frame including inner and outer walls arranged in spaced relation, each of said walls having a plurality of truck column portions, a plurality of top arch bar portions, a plurality of bottom arch bar portions, and a plurality of pedestal tie bar portions; said bottom arch bar portions being prolonged to extend over the journal boxes and having a portion 10 adapted to prevent the rotation of the journal box bolts.

17. A pressed metal car truck side frame including spaced inner and outer side walls, each of said walls being provided with an 20 opening surrounded by an inwardly projecting flange, and tie means including a tubular member bridging said side walls and having its opposite ends expanded into said flanged openings for uniting the side walls.

18. A pressed metal car truck side frame including spaced inner and outer side walls, each of said walls being provided with an opening, and tie means including a tubular member having its opposite ends expanded 30 into said opening adjacent the outer faces of said walls for uniting the same.

19. A pressed metal car truck side frame including spaced inner and outer side walls, each of said walls being provided with an 35 opening, and tie means including a tubular member having portions expanded into said opening for uniting the side walls.

20. A pressed metal car truck side frame including spaced inner and outer side walls, 40 each of said walls being provided with an opening having an inwardly projecting flange, said flanges being abutted intermediate the side walls, and a tubular tie member having portions extending into said openings for firmly uniting said side walls.

21. A car truck side frame involving a continuous blank of metal folded to form spaced inner and outer side walls, each having a plurality of truck column portions, a 50 plurality of top arch bar portions, a plurality of bottom arch bar portions, and a plurality of pedestal tie bar portions; said top arch bar portions being provided at each end with inwardly extending flanges having 55 their inner opposed edges united to produce a cambered effect and having an integral intermediate portion arranged parallel with

an axis of symmetry passing between the side walls.

22. A car truck side frame involving a 60 continuous blank of metal folded to form spaced inner and outer side walls each having a plurality of truck column portions, a plurality of top arch bar portions, a plurality of bottom arch bar portions, and a plurality of pedestal tie bar portions; said top arch bar portions being provided with inwardly extending flanges at the ends of the side frame, said flanges being folded and welded to produce a cambered compression 65 member.

23. A car truck side frame involving a continuous blank of metal folded to form spaced inner and outer side walls each having a plurality of truck column portions, a plurality of top arch bar portions, a plurality of bottom arch bar portions, and a plurality of pedestal tie bar portions; said top arch bar portions having an intermediate 70 integral portion, and inwardly extending 75 flanges adjacent said integral portion, said flanges being folded and welded to produce a cambered compression member.

24. A car truck side frame involving a continuous blank of metal folded to form 80 spaced inner and outer side walls each having a plurality of truck column portions, a plurality of top arch bar portions, a plurality of bottom arch bar portions, and a plurality of pedestal tie bar portions; said top arch bar portions having an intermediate 85 integral portion and inwardly extending flanges adjacent said integral portion, said flanges being folded and united throughout their 90 length to produce a cambered compression 95 member.

25. The method of manufacturing a car truck side frame which consists in forming the same from a continuous sheet metal blank having corresponding side frame portions which are symmetrically disposed with respect to an axis of symmetry passing between them, bending portions of said blank to form flanges, slitting opposite end portions of said blank, folding the blank along a line at the top of the side frame and intermediate the slit ends thereof, bending said slitted portions to form inwardly projecting flanges, uniting said inwardly projecting flanges, and finally uniting said first named flanges.

In testimony whereof I affix my signature.

GUSTAF A. ANDERSON.
